(57) **CLAIM**

The ornamental design for a dongle for a medical device, as shown and described.

DESCRIPTION

FIG. 1 is a perspective view of a dongle for a medical device including a translucent front portion;

FIG. 2 is a rear view thereof;

FIG. 3 is a left side view thereof;

FIG. 4 is a top plan view thereof;

FIG. 5 is a front view thereof;

FIG. 6 is a right side view thereof;

FIG. 7 is a bottom plan view thereof; and,

FIG. 8 is a rear perspective view of the dongle for a medical device mounted on a back housing member of an enteral feeding pump shown in phantom.

The elements shown in phantom form no part of the claimed design.
